UNITED STATES PATENT OFFICE.

JACOB STIRISS, OF BROOKLYN, NEW YORK.

ENVELOPE MACHINE.

Application filed October 7, 1925. Serial No. 61,127.

This invention relates to envelope machines and more especially to machines whose object is to receive the paper blank that forms the envelope and after the side flaps are folded and gummed to join the flaps with an eyelet and a cardboard washer, and a gummed protecting patch over the eyelet and within the envelope, and during this operation to affix and secure to the closure flap two cardboard washers by means of metal eyelets and securing a string by one of the eyelets, all of the washers being punched with a perforation, cut from an appropriate strip and located between the dies that carry the eyelets by plungers working in sequence as the folded blank is fed into the machine and left under said plungers. The strips of cardboard for the washers and the gummed paper strip for the protecting patch are also fed by appropriate mechanism operating at necessary periods, the incomplete envelope being successively advanced and left at rest until the final operation of affixing the patch, when it is removed to have its bottom flap gummed and closed to complete it.

These and other objects and details of the invention, together with the manner of operation of the machine, are more fully described in the following specification, set forth in the appended claims, and illustrated in the accompanying drawings, wherein:

Fig. 1 is a vertical transverse sectional view through the machine on the line 1—1 of Fig. 2, and looking towards the front of the same.

Fig. 2 is a plan view of a part of the machine and showing the actuating means for the plungers.

Fig. 3 is a horizontal sectional view of the machine on the line 3—3 of Fig. 1.

Fig. 4 is a vertical longitudinal sectional view of a portion of the machine showing the principal operating parts.

Fig. 5 is a fragmentary longitudinal section of the machine showing the operation of the plungers.

Fig. 6 is a similar view with the parts in a different position.

Fig. 7 is a view of the end of a completed envelope.

Fig. 8 is a vertical longitudinal sectional

view of a fragment of the machine showing the punching and cutting mechanism for the washers.

Fig. 9 is a transverse sectional view through the punching mechanism in line 9—9 of Fig. 8.

Fig. 10 is a detail view of the feeding and moistening device for the gummed paper.

Fig. 11 is a detail view of the knife and affixer for the gummed paper patch.

Fig. 12 is a transverse sectional view through the machine back of the bed 10 and showing the mechanism for the final advancing of the envelope and the closing of the bottom flap.

This application for patent may form a part of the machine invented and claimed by me in my application for patent filed August 26, 1921, Serial No. 495,611 and also Patent No. 1,371,270 issued to applicant March 15, 1921, for a similar machine wherein in the sides of the envelope are creased and folded preparatory to the operations of the present invention.

So much of the pending application Serial No. 495,611 may be used with the present invention after the clasp forming and affixing mechanism is eliminated. That is, the present invention is used in connection with the blank selector and feed and the flap creasers and folders, and located beyond them and with the herein described is the bottom folder and gunimer that is also shown in the said pending application.

In the accompanying drawings a bed 10 is provided and appropriately mounted with supporting frames 11 arising from the bed and in which are mounted spindles 12 and 13 respectively carrying a rocking arm 14 and 15, offset from each other and terminating about the center of the bed.

The rocking arm 14, as best shown in Fig. 4, carries at the center of the bed a plunger 16 while the arm 15 carries an adjacent plunger 17. Both of these plungers 16 and 17 carry the die members 18 and 19, respectively, and are actuated by cams 20 and 21 whose faces play on rollers 22 in the forked rear ends of the rocking arms.

Beneath the plungers and the members 18 and 19 are closing die members 23 and 24 the former movable through a passage 25 in the bed 10. The stem 23' of member 23

is hollow and through its interior plays independently a needle 26 notched at its point to engage a string 27 supplied from any desired point and normally occupying the 5 positions shown in Figs. 1 and 4.

The various moving parts of the machine are actuated from a shaft 28 driven from any desired source and having the bevelled gear wheels 29 and 30, the former meshing 10 with a similar wheel 31 on a horizontal shaft 32 beneath the bed 10 and through suitable gearing, such as the worm 33, driving the shaft 34 of the cam 35 that at certain periods elevates a lever 36 connected with the hollow 15 stem 23' to advance the closing die 23 to its operative position, as shown in Fig. 1.

The shaft 32 through worm gearing 37 also drives a cam 38 that actuates a lever 39 connected with the lower end of the 20 needle 26 to elevate same into position shown in Fig. 5 and through the flap of the envelope. Springs 40 and 41 are provided to 25 retract the levers and needle and die and at the same time hold the anti-friction rollers of the levers against the cams.

The gear wheel 30 is at the upper end of the shaft 28 and meshes with a similar wheel on the horizontal shaft 42 journaled in one 30 of the frames 11, the said shaft having the bevelled gear wheels 43 that drive identical wheels on the shafts 44 and 45 journaled in the frames and carrying the cams 20 and 21 respectively.

Running lengthwise of the bed 10 but 35 supported above it is a tongue 46 around which the envelope E is folded and moved initially by rollers 10' while its ends are open and it occupies the position shown in Figs. 1, 4, 6 and 7 when receiving the 40 washers and string.

Through this tongue is a passageway 47 opening on the upper face of the tongue and connected through the nipple 48 and pipe 49 with some air exhausting means. The 45 opening of the passageway is adapted to hold the gummed patch that is inserted within the envelope and over the joined side flaps while the envelope is moving over it and the patch is cut by the knife 20' whose 50 vertically moving plunger is operated by the lever 21' and the cam wheel 22'.

This patch of moistened gummed paper is deposited on the tongue as in the above 55 described application, Serial No. 495,611 immediately after the completed envelope passes out of the machine, being cut from a strip of gummed paper and moistened as hereinafter described. The knife 20' then rises and remains elevated until the 60 next envelope passes.

As shown in Figs. 4 and 11 the plunger 21' is operated by the lever 21' through the link 21^b and plays through the cross bar of frame 11 having on its lower face a soft 65 rubber cushion 21^c whose stem is secured in

a socket in the lower end of the plunger, while the lower edge of the knife 20' is on the level with the face of the cushion and cooperates with a blade 21^a. The plunger 21^a has two movements as indicated by the 70 rises on cam 22', the first movement cutting a patch from the gummed strip 97 which drops on the tongue and the second descent of the plunger and cushion on the eyelet F when the envelope reaches that point to 75 secure the patch over the eyelet.

Beneath each plunger 16 and 17 extend the raceways 50, (Figs. 2 and 3) for feeding the eyelets F to their appropriate positions between the closing dies 23 and 24 and as 80 the latter close, these feeding devices 50 are withdrawn leaving one eyelet on the threading needle 26 and the other on the washer beneath plunger 17.

These raceways 50 may be such as commonly used for feeding eyelets where they are needed beneath affixing plungers and are adapted to be retracted after an eyelet has been deposited and as the affixing plunger descends to operate on said eyelet. One of 90 the raceways delivers its eyelet over the tongue 46 for the die member 19 to pick it up and to locate it in the back of the envelope, while the other raceway delivers an eyelet beneath the tongue 46 and to the 95 needle 26, and after the delivery of the respective eyelets, the raceways are withdrawn by the usual mechanism commonly employed, until after the dies have operated and returned to their inoperative positions and a new envelope blank put in position for the eyeletting operation.

Figs. 2 and 3 show the raceways in their delivery position while Figs. 4, 5 and 6 show the eyelets located and the raceways withdrawn.

The mechanism above described is to affix the washers and string, the former being of a strong and tough cardboard cut from the strips 51, 52 and 53 carried on suitable reels 110 54, 55 and 56 at one side of the bed and journaled in frames 52'.

One of these strips of paper, 52, is fed along the bed 10 and the companion strip, 51, over an extension 66 of a cross bar 58, all of which is best shown in Figs. 4, 5 and 6 and both of the cross bars have perforations to allow the passage of the respective plungers 16 and 17 that play therethrough.

The device for perforating and punching 120 these washers from said strip and returning the washer to the said strip again so that it may be easily manipulated while carried by the strip to the plungers, is best shown in Figs. 1, 8 and 9, where it will be 125 seen that the shaft 45 also carries a cam 59 to rock a bell crank lever 60 whose longer arm 61 carries the plungers 62 and 63.

The plunger 63 has at its lower end a 130 punch 64 adapted to perforate the strip of

paper 51 with each revolution of the cam 59, the waste passing out of a side passage 65 of the block 66 that forms a part of the cross bar 57.

5 Through a slot beneath the block or extension 66 the paper strip 52 moves, and in a recess 67 in said block and directly beneath the punch 64 and its passage is a second punch 68 with a head 69 adapted to be engaged by vertical pins 70 depending from a collar 71 on the plunger 63 and at each side thereof and straddling the paper strip 51. Normally the punch 68 is held in its elevated position by a spring 72 but when the plunger 15 63 descends it also forces down the punch 68 and causes it to perforate the strip 52 simultaneously with the punching of strip 51, the waste paper passing out of the openings 65 and 65'.

20 After the strips have been punched, as shown in Fig. 3, the washers are cut by punches operated by a plunger 62, one of them being at the end of said plunger and encircled by the sliding sleeve 73, as shown 25 in Figs. 1 and 8, that is pressed downward and away from the collar 74 by the coil spring 75 and providing a certain amount of lost motion before operating on a ring 76 to cause it to press against the strip 51 both 30 before and after the punch 77 has passed through said strip, and so that the lower plunger 78, normally at the level of the block 66, may follow punch 77 back and replace the washer in the strip while the ring 76 is 35 depressed and held by sleeve 73.

The ring 76 effects little friction when the plunger 62 is up and lies on the moving paper awaiting the next operation of plunger 62.

40 The lower end of the plunger 78 comprises a punch 79 for the strip 52 and beneath this punch is the plunger 80 normally pressed upward by the spring 81 in the recess 82 of the bed 10 that is closed at its 45 lower end by the plate 83. Around the punch 79 is an elevating spring 84 and a sleeve 85 that is impinged by pins 86 from the ring 76 and caused to press upon the strip 52 when the strip 51 is compressed by said ring.

50 The punch 79 also cuts and removes a washer that is immediately returned to its place in the strip by the returning plunger 80 and the strip is released for the next 55 operation. Both of the springs 81 and 84 combined are weaker than the spring 75 but strong enough to force the washers back into the respective strips and the ring 76 is free to move up or down, while the sleeve 85 moves freely on the punch 79 and both ring and sleeve have slightly bevelled lower faces to allow the strip to pass under them but prevent buckling of the same.

55 Identical plungers and punches as above described are used for the strip 53 that sup-

plies the washers for the die members 16 and 17 and plungers for the latter strip are operated by the arm 61' extending from the hub of the bell crank lever 60.

The strips 51 and 52 are given motion and drawn across the machine by grippers 87 and 88 that are operated by a rocking arm 90 (Figs. 1, 2 and 3) through connecting rods 91 and the cam 20 on shaft 44, the arm 90 being drawn towards the cam 92 by means of a spring or similar device shown in Fig. 1 to return the grippers, and as will be seen in Figs. 2 and 3, a gripper 89 is operated by a cam 92 on the shaft 44 through similar mechanism as above described, to draw the strip 53 under plunger 17.

In Figs. 1 and 3 it will be seen that the grippers 87 and 88 operate in unison and comprise the slides 93 adapted to reciprocate along the bed 10 and the bar 57 while the said gripper 88 operates on a shelf 94 and the slide carries a depending arm 95 to which the gripper 88 is pivoted to operate on the table and the latter gripper is connected by the resilient rod 96 with the gripper 87, the spring on the rod being to provide a yielding pressure for the member 88.

As the arm 90 is forced outward by the rise in the cam face, the rod 91 rocks the bell crank lever comprising the jaw 87, so that the latter catches the paper strip 51 and when the jaw comes to a rest the slide 93 is then obliged to move outward on the shelf 94, the arm 95 and the two jaws, the latter advancing their respective strips.

To protect the interior of the envelope and its contents from injury by the eyelet after it is affixed by the plunger 17, a strip of gummed paper 97 is fed over the tongue 46 with its gummed side uppermost and moistened and from the same a patch D is cut to be left on said tongue and held thereon through the suction from passage 47 before the envelope is placed around the same. This patch D is shown in Figs 4, 5 and 6 and appears as applied to the envelope in the two latter views.

The gummed paper 97 is fed from the left hand side of Figs. 1, 2 and 3 (in dotted lines in Fig. 1) by means of a jaw 98 similar to the jaw 87 and comprising a bell crank lever and operated by a rod 100 also connected to the rocking arm 99 on the same shaft and adjacent the arm 90.

The operation of the jaw to moisten and advance the gummed strip is shown in Fig. 10 and is similar to a gummed strip advancer shown in the above mentioned application Serial No. 495,611 and in this instance the jaw 98 is pivoted to a sliding tank 97' and carries at its outer end a moistening wick 98' through which the strip passes so it may be moistened on the gummed or upper side. The forward movement of rod 100 throws the jaw down on a shelf in the tank and

moistens and feeds the strip far enough to form a patch. The return of the jaw and tank leaves the strip stationary but moistened as far as the tank travels by the wick 5 98'. The tank 97' is adapted to slide on the cross bar 58 being held by bolts passing through a slot.

The string 27 is fed from an appropriate source to beneath a flat spring 98² and when 10 the above operations are completed the rollers 101 and 102 at the end of the bed and ahead of the envelope, seize the latter and carry it forward when the folding bead 100' depresses the bottom flap between said rollers, as described in the aforementioned application Serial No. 495,611, to have said flap sealed and closed. The string 27 also is carried along a predetermined length and is cut by the blade 103.

20 It will be seen in Figure 4 that the roller 102 is mutilated so that after being seized, the envelope is allowed to rest during the several operations but moved at appropriate intervals and finally carried off by continually moving rollers 110' and 111'.

25 A second flat spring 98² is secured to the bed 10 but so as to exert a pressure against the bottom of the tongue 46 where it holds the string after it is cut as hereafter described. The pressure of the latter spring is less than the spring 98² so that when the needle 26 is elevated, as shown in Fig. 6, the string is drawn from under the spring 98² and its end is passed through the envelope 30 flap and is held there in the fork of the needle until the plunger 16 descends and meets the die member 23, depressing the eyelet thereon as the needle is withdrawn. For convenience of illustration in the drawings, 35 the springs 98² and 98² are shown parallel with or lateral to the tongues 46.

40 In Fig. 5 the string 27 is shown as being forced up in the perforation made in the flap of the envelope by the needle 26 where it is left and caught by the eyelet shown on said needle and the washer A on plunger 16.

45 When the latter plunger descends the string is firmly caught by the upset eyelet and the washers A and B and held so that it may be subjected to considerable strain before it can be detached from the flap G.

50 The clinching of the eyelet secures the upper washer A from the strip 51 to the upper side of the flap while the head of the eyelet secures the lower washer B and the end of the string 27 is gripped between them, at the same time gum is applied to the bottom flap.

55 The above operation is shown in Figs. 4, 6 and 7, the washer A being held over the opening in the cross bar 57 until the plunger 16 descends and carries it through the same opening and also through an opening 46' in the tongue 46, after which the washer C and 60 its eyelet are secured to the back of the en-

velope which with the washers, and string attached has the gummed patch applied and is carried to the final operation of closing the bottom by the rollers 101 and 102. The loose end of the string follows the envelope 70 and the knife 103, playing through an opening in the bed 10, moves upward and cuts the same after an appropriate length had followed said envelope. At this operation the envelope flap has passed the range of the 75 knife and the string 27 again occupies the position and condition shown in Figs. 5 and 6.

The knife 103 is carried by a plunger 104 that is actuated by a lever 105 having a 80 roller 106 playing on the cam 107 carried by the shaft 34 and as the envelope passes out, the string 27 is drawn across the end of the needle 26 and left in position to be again caught for the next operation.

85 The raceways 50 with the eyelets are also moved into position so that the eyelets may be deposited in the perforations of a new washer C and on the needle 26, and the latter forces the eyelet through the lower washer 90 and the flap of the new envelope preparatory to having said eyelet clinched.

95 The envelope is fed into the machine and around the tongue while the sides are closed and sealed but before the bottom is folded and sealed.

Suitable springs are shown to return the parts to their normal positions and gearing is provided to operate them.

100 In Figure 4 it will be seen that while the feed roller 102 is continuously driven, it is mutilated so that it fails to feed after the blade 102' descends and the envelope is advanced far enough to have the plunger 20' affix the gummed patch. The envelope is 105 then taken up by rollers 101 and 102 again and moved to bring the latter into the influence of rollers 110, and 111, the knife 110 controlled by cam 107 cuts the string 110 to a predetermined length while the envelope is in motion.

115 The mechanism connecting and driving the intermittent envelope feed and the advance of the various strips above mentioned is best shown in Fig. 12 where the shaft 34, that also appears in Figs. 1 and 4, is provided with a worm 122 near its rear end and which meshes with and drives a worm wheel 123 on the shaft of the roller 110 that also carries the gear wheel 124 to drive the gear wheel 125 on the shaft of roller 101. A gear wheel 126 meshes with a larger gear wheel 127 on the shaft of the paste pot feed 128 and its cams 129 and 130.

120 By this arrangement the various plungers and strip feeds are operated in unison with the intermittent feed of the envelope through the machine and the entire operation may be from one source.

125 After the envelope has been carried off

the tongue 46 the moistening jaw 98 is advanced, feeding the gummed patch beneath the plunger 21^a which descends far enough to cause the blade 20' to cut off a patch that 5 falls on the tongue being attracted by the air suction through passage 47 and held firmly on the said tongue before a new envelope blank is fed over it.

While Fig. 6 shows the practically complete envelope in section, Fig. 7 shows the back of same with the disk A cut from the strip 51, the string 27 and the gummed patch at the inside of the back of the envelope; and the closure is effected by folding 15 down the flap G and clamping the string 27 under the washer C and about its eyelet F.

As shown in Fig. 4 after the envelope passes through rollers 101 and 102 it is fed on by rollers 110 and 111 and between the 20 cylinders 112 and 113, the former adapted to carry a stereotype plate 114 that is inked by the rollers 115 and makes an impression on the bedding 116 of the cylinder 113, so that any desired printing may be done on 25 the envelope as it passes through the machine, thus reducing labor where a complete printed envelope is desired.

The cylinder 113 also carries an adjustable bar 117 adapted to gather up paste 30 from the roller 118 located in the paste pot 119 and when it is desired to also apply paste to the flap in addition to the string closure. The cylinder 112 may be provided with a flexible strip 120 against which the 35 bar with the flap impinges.

It is obvious that the parts may be otherwise arranged and modified without departing from the essential features above described or from the scope of the appended 40 claims.

What I claim is:

1. In an envelope machine, the combination of feeding means for an envelope, closing dies adapted to attach an eyelet with 45 washers and a string to the flap of said envelope, dies adapted to attach an eyelet and washer to the rear-side of the envelope, and means adapted to secure a protecting patch within the envelope, the operations 50 being consecutive and as the envelope is passing through the machine.

2. In an envelope machine, the combination of means for feeding an envelope, means 55 for inserting an eyelet and string in the flap of the envelope, means for inserting an eyelet and washer in the back of the said envelope, means for inserting a gummed patch within the envelope and over the inner end of the eyelet, and a tongue around 60 which the envelope is adapted to travel and to support the patch until it is affixed over the inner end of the eyelet.

3. In an envelope machine, the combination of means for supporting and feeding an 65 envelope, means for attaching an eyelet

with a string to said envelope, means for attaching a second eyelet with a washer to said envelope, and means for afterwards securing a patch to the envelope to cover one end of the latter eyelet. 70

4. In an envelope machine, the combination of means for carrying and guiding an envelope, intermittent-means for advancing the envelope, means for depositing a 75 gummed patch on the carrying and guiding means, a plunger adapted to affix an eyelet and a string to said envelope, a plunger adapted to affix a second eyelet and washer to the back of the envelope, and means for affixing the gummed patch to the envelope 80 to cover the end of the latter eyelet within said envelope.

5. In an envelope machine, the combination of means for intermittently feeding an envelope through the said machine, a guide 85 adapted to carry the envelope, means for feeding strips of paper across the envelope and guide, means for cutting washers from the strips and affixing them to the envelope, means for feeding a strip of gummed paper 90 across the guide, and means for cutting a patch from the gummed strip and depositing same on the guide.

6. In an envelope machine, the combination of a guide for the envelope, rollers 95 adapted to feed the envelope over the guide, means for feeding strips of paper across the machine above and below the guide, means for cutting washers from the strips, means for restoring the washers to the strips, and plungers adapted to secure the washers to the envelope while it is at rest. 100

7. In an envelope machine, the combination of mutilated feed rollers adapted to intermittently advance an envelope through 105 the machine, a guide tongue adapted to carry an envelope, a needle adapted to carry and locate a string, and plungers adapted to place and clinch an eyelet to secure washers punched from strips of paper adapted to move laterally to the envelope and to secure the said string to the envelope.

8. In an envelope machine, the combination of feed rollers at each side of the machine and adapted to move an envelope, a 110 guide tongue between each pair of feed rollers and adapted to carry an envelope, means for cutting washers from a strip of paper and feeding them under the tongue, means for feeding a string adjacent the washers, and a plunger adapted to act on an eyelet to secure the washers and string to the flap of an envelope. 115

9. In an envelope machine, the combination of feed rollers for an envelope at 120 each side of the machine for advancing an envelope, a guide tongue suspended in the centre of the machine, eyelet carriers, plungers with closing dies above and below the said carriers, a needle playing in one of 125 130

the plungers and adapted to manipulate a string, means for carrying washers above and below the tongue, and means adapted to operate the plungers when the envelope is at 5 rest to attach thereto the washers and the string by means of an eyelet.

10. In an envelope machine, the combination of feed rollers for the envelope, a tongue suspended between the rollers and 10 adapted to have the unfinished envelope folded around it, plungers adapted to affix washers and a string to the flap of the envelope, and a plunger adapted to affix a washer with a gummed patch to the back 15 of an envelope.

11. In an envelope machine, the combination of feed rollers for an envelope, supporting and guiding means for an envelope, co-operating closing dies adapted to operate at 20 each side of the envelope flap, means for feeding strips of paper carrying washers at each side of said flap, a needle adapted to carry a string and an eyelet, and means for operating the dies to close the eyelet on the 25 washers and the string while the envelope is at rest.

12. In an envelope machine, the combination of a bed having upright frames, means for supporting and intermittently feeding an 30 unfinished envelope through the machine, a lower die playing through the bed, an upper die carried from the frame, a needle playing through the lower die and adapted to carry an eyelet and manipulate a string, means 35 carrying a strip of washers above and below the closure flap of the envelope, and means operating the dies in unison.

13. In an envelope machine, the combination of a bed having upright frames, a cross 40 bar having a perforation, means for feeding a strip of paper comprising washers and supported by the cross bar, a plunger and die playing through the perforation in the cross bar and adapted to carry a washer in 45 its downward movement, means for feeding a second washer strip, a cooperating plunger and die playing through the bed, a needle playing through the latter plunger and adapted to carry an eyelet and a string; and 50 means for operating the plungers to clinch the eyelet and affix a washer and string to the flap of an envelope as it is intermittently carried through the machine.

14. In an envelope machine, the combination of a bed having upright frames, a cross 55 bar between frames and having a perforation, means for feeding strips of paper comprising washers and adapted to be fed across the machine, a downwardly moving die and 60 plunger adapted to carry a washer, a lever carrying the plunger, a cam operating the lever, an upwardly moving plunger and die, a needle operating independently in the latter plunger and adapted to carry an eye- 65 let and a string, a cam and lever adapted

to operate the upwardly moving plunger, and a cam and lever adapted to reciprocate the needle.

15. In an envelope machine, the combination of a bed, intermittent feed rollers, an envelope supporting guide, plungers adapted to affix washers and a string to the closure flap of an envelope, a plunger adapted to close and affix a washer and gummed patch to the back of the envelope, a carrier for 70 eyelets below the plunger, means for actuating a strip of paper comprising washers, and adapted to be fed over the supporting guide, means for feeding a strip of gummed paper above the guide, means for cutting 75 a patch from the same, means for operating the plunger to clinch the washer to the back of the envelope by means of an eyelet from the carrier, and means for applying the 80 patch. 85

16. In an envelope machine, the combination of a bed having upright frames, intermittent feed rollers, an envelope supporting guide, means for affixing washers and a string to the closure flap of the envelope, a plunger with a closing die, a cooperating 90 die carried by the guide, a removable eyelet carrier above the latter die, means for feeding a gummed strip adapted to be fed under the back of the envelope, means for operating the plunger to clinch the eyelet with the washer, and means adapted to affix the 95 gummed patch.

17. In an envelope machine, the combination of a bed having intermittent feed 100 rollers, a supporting tongue for the envelope, means for feeding strips of paper comprising washers, gripping jaws adapted to be reciprocated across the bed to drag and feed the strips, a knife adapted to cut a gummed 105 strip of paper into patches, a sliding tank reciprocated by a cam, a gripping jaw adapted to advance the gummed strip, a wick carried by the jaw extending into the tank and adapted to moisten the gummed strip, means for attaching a washer and a patch to an envelope, a spring adapted to hold a string against the under side of the tongue, a second and stronger spring 110 adapted to hold the string against the bed, a needle adapted to engage the string and force it through the flap of the envelope, and means for securing the string to the flap 115 of an envelope between the washers and by the aid of an eyelet. 120

18. In an envelope machine, the combination of a bed, means for advancing strips of paper adapted to be dragged and fed across the bed of the machine, gripping jaws adapted to be reciprocated across the said bed, a perforating punch adapted to penetrate a strip, a second punch beneath the first mentioned punch and adapted to penetrate a second strip, means connected with the first punch 125 for operating the second, means for cutting 130

and restoring washers in the strips, and means for attaching the washers and a string to an envelope.

19. In an envelope machine, the combination of a bed, means for advancing paper strips adapted to be drawn across the bed, gripping jaws reciprocated and engaging the strips, a punch adapted to perforate the strip, a lower punch adapted to perforate another strip, lateral pins from the upper punch adapted to straddle the upper strip and operate on a head on the lower punch, means for cutting washers from the perforated strips and restoring them, means for attaching washers and a gummed patch to an envelope, and means for attaching other washers and a string to the flap of the envelope.

20. In an envelope machine, the combination of a bed, an envelope carrying tongue, means for intermittently advancing a paper strip adapted to be dragged across the bed, means for perforating the strip, a punch adapted to cut washers from the strip of paper, a spring pressed sleeve adapted to hold the strip before and after the washer is cut, means for replacing the washer in the strip of paper, and means for advancing the strip.

21. In an envelope machine, the combination of a bed, having an envelope guiding tongue, means for advancing strips of perforated paper adapted to be fed over and under the tongue and across the bed, a punch adapted to cut a washer from the upper strip, a second and spring pressed punch below the first punch and whose upper end is adapted to return and replace the washer to its strip when the first punch releases it, a yielding sleeve on the first punch, a spring pressed plunger below the second punch to restore the washer to the second strip, and rings operated by the sleeve and adapted to press on the strips before and after the washers are cut.

22. In an envelope machine, the combination of a bed having an envelope guiding tongue, means for intermittently feeding strips of paper adapted to pass over and under the tongue, punches adapted to cut washers from the strips to be applied to an envelope, plungers adapted to return the washers to the strips, rings adapted to compress the strips while the washers are being cut and restored, a spring pressed sleeve adapted to operate the rings and allow their release from the paper strips when the latter are fed, and means for releasing the washers and affixing them to an envelope.

23. In an envelope machine, the combination of a bed having an envelope guiding tongue, means for intermittently advancing strips of perforated paper adapted to be fed over and under the tongue, a punch for the upper strip and adapted to cut washers concentric with the perforations that are to be applied to the envelope, a second punch for the lower strip and having a plunger at its upper end to restore the washer to its strip, a spring to elevate the latter punch and plunger, a second plunger below the lower punch to restore its washer, a spring for the second plunger, a ring above the upper plunger, a sleeve above the lower plunger, pins connecting the ring and sleeve, and a spring pressed sleeve in advance of the first punch and adapted to force the ring and the first sleeve against their respective strips before and after their washers are cut.

24. In an envelope machine, the combination of an envelope supporting tongue having a passage through the same, that is provided with an outlet, an air exhaust tube connected with the passage, means for intermittently feeding a gummed strip, a knife adapted to cut a patch from the strip when located over the outlet, means for feeding and moistening the strip, intermittent feeding means for an envelope and adapted to advance the same over the patch while being held by the air exhaust, a strip of paper carrying washers and adapted to be dragged over the gummed strip and outside of the envelope, means for cutting and replacing the washers, and means for attaching the washer by means of an eyelet and the gummed patch by compression to cover the head of the eyelet within the envelope.

25. In an envelope machine adapted to have an envelope passed through it, of means for cutting washers from strips of paper and retaining the cut washers in the strips, means for feeding the strips and washers over and under a tongue carrying an envelope, means for attaching a washer and an eyelet to the back of the envelope, means for attaching a washer and a string to the flap of the envelope, and means for feeding, and means for cutting and attaching a gummed strip of paper within the envelope and over the eyelet, all of the operations being performed as the envelope intermittently passes through the machine and during one single revolution of the feeding drum.

In testimony whereof I hereunto affix my signature.

JACOB STIRISS.
